UNITED STATES PATENT OFFICE

162,784

PIE MOLDING AND FILLING MACHINE UNIT

Harold Burke, Birmingham, England, assignor to
Concentric Manufacturing Company Limited,
Birmingham, England

Application March 1, 1949, Serial No. 1,139
In Great Britain January 21, 1949

Term of patent 7 years

(Cl. D55—1)

To all whom it may concern:

Be it known that I, Harold Burke, a subject of the King of Great Britain, residing at Birmingham 24, Warwickshire, England, have invented a new, original, and ornamental Design for a Pie Molding and Filling Machine Unit, of which the following is a specification, reference being had to the accompanying drawings, forming part thereof.

Fig. 1 is a perspective view showing the front and one side, Fig. 2 is a perspective view showing the front and other side, Fig. 3 is a perspective view showing the rear and Fig. 4 is a perspective view showing the top of a pie molding and filling machine unit embodying my new design.

I claim:
The ornamental design for a pie moulding and filling machine unit, as shown.

HAROLD BURKE.
